UNITED STATES PATENT OFFICE.

JAMES H. DENNEDY, OF DETROIT, MICHIGAN.

ARTIFICIAL REFRIGERATING SYSTEM.

Application filed December 10, 1921. Serial No. 521,427.

To all whom it may concern:

Be it known that I, JAMES H. DENNEDY, a citizen of the United States, residing at Detroit, county of Wayne, State of Michigan, have invented a certain new and useful Improvement in Artificial Refrigerating Systems; and declare the following to be a full, clear, and exact description of the same, such as will enable others skilled in the art 10 to which it pertains to make and use the same, reference being had to the accompanying drawings, which form a part of this specification.

This invention relates to artificial refrigerating systems in which a refrigerant body such as sulphur dioxide, methyl chloride or similar chemical is compressed and liquefied and then cooled and allowed to expand in a coil within a storage compartment, brine tank or the like, and the particular feature of this invention is in the provision of means to control the temperature of the storage compartment or body to be cooled through variation in pressure of 25 the expansion side of the system. The apparatus is intended to be operated by an electric motor as is usual with systems of this character but other motive power may be utilized if desired. The means employed 30 for stopping and starting the electric motor, as is preferably used, is an electric switch adapted to connect and disconnect the motor with the source of energy. Heretofore, the temperature of the storage compartment 35 is maintained between certain high and low limits by means of a thermostat which is adapted either through the expansion and contraction of a bi-metallic element or actuation of other means sensitive to temperature 40 change to open and close the circuit to the motor. In the apparatus herein disclosed a pressure controlled switch is utilized subject to the influence of variation in pressure in the expansion side of the system, a 45 certain high pressure resulting in the closing of the switch to start the system into operation, and a predetermined low pressure opening the switch and causing cessation of operation of the motor, the switch 50 being adjustable to permit the device to be set to operate at different pressures. An automatically operating valve is also employed between the high and low pressure sides of the circulating system and preferably with a pressure operated device for 55 maintaining the temperature of the storage

compartment within certain limits. I prefer to employ an automatic valve of a character to maintain a constant quantity of refrigerant in the expansion side of the system. 60 In systems of this general character, upon cessation of operation of the compressor, the pressure on the low pressure sides of the system tends to increase due to absorption of heat from the body or compartment being 65 cooled. With a pressure controlled device controlling operation of the refrigerating apparatus, the pressure of the expansion side may be held between certain limits of high and low pressure by which means the 70 temperature of the refrigerated compartment is directly controlled by the apparatus herein disclosed.

This application constitutes a continuation in part of my application Serial No. 75 493,266, filed August 18, 1921, covering artificial refrigerating apparatus.

The drawing presented herewith illustrating the preferred form of apparatus embodying my invention is practically 80 diagrammatic in form showing a compressor indicated at 1, a compartment or body to be refrigerated indicated at 2, the high pressure side of the circulating system, including a condenser, indicated at 3, and the 85 low pressure side indicated at 4, the low pressure line having a coil 5 (which may be of any desired form) located within the storage compartment or body to be refrigerated, the temperature of which it is desired to control. As will be readily understood, the coils 5 may be used in a brine tank or in conjunction with any other body desired to be used. 90

The control apparatus is indicated generally by the numeral 6 and is on a much larger scale in comparison to the compressor than would be the case in actual construction, being here shown on an enlarged scale to more clearly show the several parts 100 of the device in detail.

The compressor 1 may be of any approved type preferably one operated by an electric motor (not here shown) connected with the shaft 7 of the compressor, it being understood that the compressor discharges into the line 3 which is connected to the upper end of the casing and receives its supply from the line 4. Between the high pressure line 3 and low pressure line 4 and coil 5 of 110 the expansion side, I provide an expansion valve indicated generally by the numeral

70. I do not wish to be understood as limiting myself to the use of the particular form of expansion valve here shown but prefer to use this type of valve which is 5 of a character to maintain a constant volume of refrigerant in the low pressure side of the system. The valve shown consists of a valve member 8 of needle type adapted to open or close the end of the line 10 4 opening into the chamber 9 in which the valve is positioned. This valve 8 is pivotally supported on a block 10 which is pivoted to a base 11. Secured to this block 10 is a float consisting of a hollow ball 12 on the 15 rod 13. The rise in level of fluid in the case 9 will raise the float 12 and open the line 4 to a flow of fluid thereinto and a fall in the level of the fluid in the chamber 9 closes the line 4 to the high pressure side of the system. 20 It is therefore to be seen that with this valve the fluid is passed from the high pressure side to the low pressure side solely by variation in level of the fluid in the chamber 9 tending to maintain a certain volume of 25 fluid at the high pressure side and pass fluid into the low pressure side as rapidly as it is removed therefrom.

With any refrigerant, the temperature of the liquid refrigerant or its saturated vapor 30 in the expansion coil of the system bears a definite relation to the pressure thereof—that is, for instance with sulphur dioxide, a gauge pressure of approximately 4.6 pounds per square inch indicates a temperature 35 of the liquid refrigerant or its saturated vapor of 25 degrees F., and with a gauge pressure of 2.5 pounds per square inch the temperature of the sulphur dioxide is approximately 20 degrees F., and I have taken 40 advantage of this fact by this pressure control device which is directly connected by means of a line 14 with the expansion line 4. The pressure control device consists of a casing 15 within which is a circumferentially 45 corrugated cylinder 16 of well known type capable of expansion and contraction longitudinally of its axis. The lower end of this member 16 is sealed to a plate 17 and the upper end is sealed to a cover 18 set in 50 place on the casing 15. This provides a sealed chamber 19 between the corrugated member 16 and casing 15, the chamber 19 being open to the line 14. As shown in the drawing, the plate 17 is at its lowermost 55 position engaging against the upper end of the inlet for the line 14 but on pressure accumulating in the line 4 and 14, this member 17 is raised. Within the corrugated cylinder 16 is a spring 20 engaging at the 60 upper end against a cap 21 and at the lower end against the member 17, the spring tending to expand the member 16 and force the member 17 to the lowermost position as shown in the drawing. A rod 22 is carried in the base member 17 and extends up-

ward through the cap to an electric switch of the knife blade type which, it is to be understood, has a blade 23 adapted to be brought into engagement with the contact member 24 of the control circuit wires 25 70 and 26. Upward movement of the member 17 and rod 22 caused by an increase in pressure in the line 4, as will be understood, will close the switch and close the circuit to the electric motor starting the same and operating the compressor, and a decrease in pressure in the line 4 sufficient to permit the spring to act and force the member 17 downward to the position shown in the drawing opens the switch, cutting the current supply off from the motor and thus stops operation of the compressor.

The operation of the system will be understood from the following: Let it be assumed that it is desired to maintain the storage compartment or body to be cooled at a temperature ranging from 25 to 30 degrees F., and let it be assumed that sulphur dioxide is used as a refrigerant. The principle of operation will apply to any 90 refrigerant but the numerical values depends upon the particular refrigerant used. The amount of heat passed through any conductor in a unit of time may be expressed by the equation $Q = A \times (T' - T'') \times C$ 95 in which Q equals the quantity of heat transmitted in a unit of time and therefore is the rate of flow of heat through the conductor. A equals the effective area of the conductor through which the heat 100 will pass. T' equals the temperature of the source of heat—that is in this instance the temperature of the body to be cooled. T'' equals the temperature of the medium which absorbs or takes up heat from the 105 warmer bodies and in this case is the temperature of the boiling refrigerant. C equals the coefficient which becomes a constant for similar conditions.

In any refrigerating system with the compressor running at constant speed, Q is practically a constant quantity. A is also constant when a float valve is introduced as shown here to control the flow of compressed refrigerant from the chamber 9 into the expansion coils 4, and C is constant for any type of system when conditions are similar and therefore the quantity $T' - T''$ is also constant (here assumed to be 10 degrees F., for the purpose of illustration) while the 120 system is in operation. The value of $(T' - T'')$ can be varied as conditions may require.

If the temperature of the storage compartment is 30 degrees F., and it requires 10 degrees difference to force heat through the available area of the expansion coil 5 at the required rate, then the temperature of the refrigerating medium must be 20 degrees F., and with sulphur dioxide the pressure in 130

the evaporating or expansion coil must be approximately 2.5 pounds per square inch gauge pressure. As the machine continues to operate and heat is absorbed from the storage compartment the temperature thereof falls finally reaching the minimum of 25 degrees F., at which time the temperature of the refrigerant in the expansion coil must be 15 degrees F., and has a gauge pressure of one-half pound per square inch. Under this reduced pressure by action of the spring 20 the switch will be opened stopping operation of the motor and compressor. As the storage compartment reaches a temperature of 25 degrees F., and the temperature of the liquid in the coil 5 is 15 degrees F., heat will continue to flow from the compartment into the refrigerant.

Inasmuch as the compressor is stopped 20 at this time this additional heat flowing into the refrigerant body will cause an increased pressure in the line 4 and coils 5 and when this pressure reaches about 4.6 pounds per square inch gauge pressure, vaporization 25 will cease because the temperature of evaporation of sulphur dioxide at 4.6 gauge pressure is 25 degrees F. Under these conditions, when the storage compartment has reached a temperature of 30 degrees F., the refrigerant body in the expansion coils has also reached the same degree of temperature at which temperature the pressure in the evaporating coils will be about 7 pounds per square inch which will close the switch 35 and start the motor. The starting and stopping of the apparatus is thus controlled by variation in pressure of the low pressure side of the system and the temperature of the storage compartment is maintained 40 within a 5 degree range and there is thus available a difference of pressure of 6.5 pounds per square inch for actuating the control switch. The data given refers only to stated temperatures but the switch member is made adjustable by varying the tension of a spring so that any desired range 45 of temperature at which it would be desired to maintain a storage compartment can be compensated for. With a thermostatically controlled switch the starting and stopping 50 of the mechanism would be through a range of 2.4 pounds per square inch because the pressure corresponding to a temperature of 30 degrees F., is 7 pounds and the pressure corresponding to 25 degrees F. is 4.6 pounds 55 per square inch gauge pressure. By the arrangement here described a relatively large difference in pressure is made available for operation of the switch permitting only a 60 relative small variation in temperature of the cooling body.

It is evident from the foregoing that the device is simple and inexpensive; that the temperature of the storage compartment 65 may be accurately maintained by the varia-

tion in pressure of the expansion line rather than by the temperature of the body or storage compartment being cooled and by the use of the float controlled valve, the liquid refrigerant is automatically transferred 70 from the high to low pressure side practically as fast as it accumulates, and a practically constant maximum quantity of refrigerant maintained in the evaporating line which is the condition under which the most 75 efficient results are obtained.

Having thus fully described my invention, what I claim and desire to secure by Letters Patent of the United States is—

1. In an artificial refrigerating apparatus 80 including a compressor, a body to be refrigerated, and a circulating system for the refrigerant having a high and a low pressure side, the low pressure side being arranged to effect temperature changes in the body to be refrigerated, the combination therewith of valve means automatically actuated to pass refrigerant from the high to the low pressure side only upon an increase 85 of the quantity of liquid refrigerant in the high pressure side above a predetermined amount, and a control device for stopping and starting operation of the compressor operated through variation in pressure of 90 the refrigerant in the low pressure side of the system caused by variation of temperature in the refrigerant in the low pressure side.

2. In an artificial refrigerating system including a power apparatus, a compressor, high and low pressure lines for circulation of a refrigerant, of a float controlled valve arranged to automatically discharge refrigerant from the high to the low pressure side on an increase in quantity thereof in the high pressure side above a predetermined amount, a control device for starting and stopping the power apparatus and operation of the compressor, means for actuating the control device comprising an apparatus 100 sensitive to variation in pressure in the low pressure line due to temperature change therein, and a body to be cooled providing the sole means through which the low pressure line is subjected to influence of heat.

3. In an artificial refrigerating apparatus including a compressor, a circulating system having a high and low pressure side, and a power appliance, the combination therewith of a device for controlling operation of the system comprising apparatus operating in conjunction with the compressor to maintain a substantially constant quantity of the refrigerant in the low pressure side, and means operated by variation in the vapor tension of the low pressure side to stop and start the power appliance.

4. In an artificial refrigerating apparatus including a compressor, operating means therefor and a circulating system for the

- refrigerant having a high and low pressure side, of a refrigerator having a chamber to be cooled in which the low pressure side of the system is located, means operating in 5 conjunction with the compressor for maintaining a predetermined quantity of refrigerant in the low pressure side, and a control device for starting and stopping the power apparatus including a chamber open to the low pressure side of the system, and means in the chamber influenced by variation in pressure of the low pressure side to start and stop operation of the power apparatus.
- 10 5. The combination in an artificial refrigerating system of a refrigerant circuit including a low pressure side and a high pressure side, a compressor, means for maintaining a constant volume of liquid refrigerant in the low pressure side, comprising a float valve actuated by fluctuation in the level of liquid refrigerant in one of said sides, means responsive to pressure variations in the low pressure side due to temperature change thereof for controlling said compressor, and a body to be cooled, absorption of heat in varying amount by the low pressure side being substantially confined to heat from said body.
- 15 6. In an artificial refrigerating apparatus including a compressor, a body to be refrigerated and a circulating system for refrigerant having a high and a low pressure side, the low pressure side being arranged to effect temperature changes in the body to be refrigerated, the combination therewith of a valve for passing liquid refrigerant from the high pressure side to the low pressure side, the liquid refrigerant forming a trap to prevent passage of vaporized refrigerant from said high pressure side through said valve, means for closing said valve when there is insufficient liquid for said trap, and a control device for said compressor, operating through variation in pressure in the 20 refrigerant in the low pressure side of the system caused by variation of temperature of the refrigerant in said low pressure side.
- 25 7. A refrigerating apparatus comprising a circulating system having a low pressure side in heat absorbing relation to the body to be cooled for containing and vaporizing refrigerant, means for withdrawing vaporized refrigerant from the low pressure side, means responsive to pressure change in the vaporized refrigerant in the low pressure side for controlling said withdrawing means, and means for automatically supplying liquid refrigerant to the low pressure side as required for maintaining a constant area 25 of heat absorption for the liquid refrigerant.
- 30 8. A refrigerating apparatus comprising a refrigerant circulating system having a low pressure side forming a vaporizing chamber in heat absorbing relation to the body to be cooled, means for withdrawing vaporized refrigerant from the low pressure side, means for returning liquid refrigerant to the low pressure side and for maintaining a constant level of the liquid refrigerant therein, and means responsive to fluctuation 70 in the vapor pressure in the low pressure side for controlling said withdrawing means.
- 35 9. An artificial refrigerating system comprising a high pressure side and a refrigerant flooded low pressure side, means for delivering liquid refrigerant from the high pressure side to the low pressure side, means for withdrawing vaporized refrigerant from the low pressure side, a body to be refrigerated with which the low pressure side is in heat absorbing relation, means for maintaining a constant area of exposure with the body of the liquid refrigerant in the low pressure side, and means responsive to pressure fluctuations in the low pressure side for controlling withdrawal of liquid refrigerant from the low pressure side by said withdrawing means.
- 40 10. The combination in a refrigerating apparatus, of a vaporizing chamber, a body to be cooled in heat imparting relation thereto, means for admitting liquid refrigerant to said chamber, means for reducing the pressure in said chamber, means for keeping a constant area of heat absorption between the body and the liquid refrigerant in the chamber, and means for controlling said pressure reducing means in response to pressure fluctuation in the chamber.
- 45 11. The combination with a refrigerating apparatus comprising a high pressure side, a low pressure side in heat absorbing relation to the body to be cooled, means for withdrawing vaporized refrigerant from the low pressure side and for returning it in compressed form to the high pressure side, and means responsive to pressure fluctuations in the low pressure side for controlling said first mentioned means, of means for passing sufficient liquid refrigerant from the high to the low pressure side to maintain a constant area of liquid refrigerant exposed to the body to be cooled but preventing passage of vaporized refrigerant.
- 50 12. A refrigerating apparatus comprising a high pressure side for containing liquid refrigerant, a low pressure side for vaporizing the refrigerant, a body to be refrigerated constituting practically the sole source of heat absorbed by the low pressure side, valve means between the high and low pressure sides automatically keeping the low pressure side flooded with liquid refrigerant whereby the vapor pressure in the low pressure side bears a definite relation to the temperature thereof, exhausting means for lowering the pressure in the low pressure side, and means actuated in response to fluctuation in vapor pressure in

the low pressure side for controlling the functioning of said exhausting means for the purpose of maintaining the pressure, and thereby the temperature, of the low pressure side between predetermined limits.

13. In a refrigerating apparatus the combination of a refrigerant circulating system having a high pressure side for containing liquid refrigerant and a low pressure side for vaporizing the refrigerant, means for passing liquid refrigerant from the high pressure side to the low pressure side, a body to be cooled in heat transferring relation to the low pressure side and supplying substantially the only heat absorbed thereby, exhausting means for lowering the pressure in the low pressure side, and means actuated by fluctuations of the vapor pressure in the low pressure side in response to temperature fluctuations therein to control said exhausting means for keeping the temperature of the low pressure side within predetermined limits by maintaining the vapor pressure therein between predetermined limits.

In testimony whereof, I sign this specification.

JAMES H. DENNEDY.
